UNITED STATES PATENT OFFICE.

WILLIAM M. WILKIN, OF MOBILE, ALABAMA.

GANG-SAW MILL.

SPECIFICATION forming part of Letters Patent No. 761,344, dated May 31, 1904.

Application filed April 18, 1903. Serial No. 153,238. (No model.)

To all whom it may concern:

Be it known that I, WILLIAM M. WILKIN, a citizen of the United States, residing at Mobile, in the county of Mobile and State of Alabama, have invented certain new and useful Improvements in Gang-Saw Mills; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

My invention relates to gang-saw mills; and it consists, substantially, in certain new and improved features therein and the combination of these improvements with a gang-saw mill.

As gang-saw mills are now constructed serious difficulties are encountered in operating them in quarter-sawing lumber and in sawing two small logs at the same time. To overcome these difficulties, I construct each of the press-rolls of the gang with one or more annular V-shaped grooves, and on the center of the press-roll yokes I mount a third roll provided with a V-shaped groove, so that the grooves in each of the rolls are adapted to engage the edge of a quarter-sawed or the round-edged upper surface of a small log, as the case may be, and effectually prevent its tipping sidewise while passing under the press-rolls and being sawed. To further contribute to this result, I place a cylinder across the front of the mill provided with cutters projecting up to the top of the feed-rolls of the mill, which operates as the quarter-log or round log is moved under the press-rolls and upon the feed-rolls of the mill to skive off the bottom of the quarter-log or log, so that when it passes upon the feed-rolls of the mill this flattened surface rests upon and is engaged by them and serves to prevent the log or quarter-log from rolling thereon.

Another feature of my invention is in the construction and combination, with the mill, of an improved log-feedway for carrying quarter-logs or logs into the mill.

The features of my invention are herein-after fully set forth and explained, and illus-

trated in the accompanying drawings, in which—

Figure 1 is a front end view in elevation of my improved gang-saw mill with the log-feedway removed. Fig. 2 is a side view in elevation of the same with sections of the log-feedway.

In the drawings illustrating my invention, A is the frame of the mill, B the saw-sash provided with saws b, C the crank-shaft, C' the driving-pulley thereon, D D' the pitmen-cranks, D' D' the pitmen connecting the pitmen-cranks D D with the saw-sash B, E the counterweight-crank, E' the counterweights swinging on arms E' pivoted to supports e' on the base of the frame A, e the counterweight-pitmen, F F the feed-rolls, and G G' H H' h h' the feed-roll-operating mechanism, all of which are of the usual and ordinary construction.

On the edges of the frame A, I provide removable guides I I, upon which I mount press-roll yokes J J, adapted to slide up and down freely thereon, and on rocking levers K, centrally pivoted in the press-roll yokes J, I mount auxiliary press-roll yokes J' J', moving freely up and down in recesses in the main press-roll yokes J. These features are sufficiently shown in dotted lines in Fig. 1, as they do not form an important feature of this invention, as the press-rolls can be mounted on the press-roll yokes J in the usual manner, if desired.

The press-rolls L L, as shown herein, are mounted in the auxiliary press-roll yokes J' J' and are each provided with one or more annular V-shaped grooves l, adapted to engage the upper edges of different-sized quarter-logs, as illustrated in dotted lines in Fig. 1, so that both may be sawed at the same time. On the center of the press-roll yokes J, I also mount short press-rolls L', with a V-shaped peripheral groove therein adapted to engage the upper edge of a larger quarter-sawed when the press-roll yokes J are moved up, as is also illustrated by dotted lines in Fig. 1, the object of the V-shaped grooves in the press-rolls being to engage the upper edges or corners of quarter-logs, so that they will be firmly held upright while being sawed.

For operating the press-roll yokes J J, I mount steam or compressed-air cylinders M in the base of the frame A, one on each side thereof, from the piston-rods *m* of which 5 links *m'* extend to arms *n* on rock-shafts N, mounted in the frame A below the plane of the feed-rolls F F, and from the arms *n n'* on the rock-shaft links *n''* extend up at each side of the frame A to studs *j j* on the ends of the 10 press-roll yokes J J, by means whereof the press-roll yokes J J and the mechanism thereon are actuated by the pistons of the cylinders M M, as is shown in another application filed herewith and pending therefor. At the 15 front of the mill I mount a transverse cutting-cylinder O, having cutters *o*, preferably staggered, on the periphery thereof which extend up to the plane of the tops of the feed-rolls F F, and on the frame A under the press-rolls L L on the same plane with the feed-rolls F F, I mount an auxiliary feed-roll O', 20 driven by a sprocket-chain *f* from one of the feed-rolls F and adapted to support the end of the quarter-log or logs until they pass upon 25 the regular feed-rolls F F. On the periphery of the feed-disk G, I place a band-rim *g*, from which a belt *g'* extends to a pulley O² on the end of the shaft of the cylinder O and operates to drive the same. In the drawings I 30 have shown the bearings *p* of the cylinder O mounted on brackets P P on the mill-frame; but it is obvious that, if desired, the bearings of the cylinder O may be mounted on suitable supports independent of the mill-frame or on 35 vertically-adjustable supports on the mill-frame or otherwise, as the cylinder O will in either case perform its function with equal facility—viz., the skiving off of the under surface of the quarter-logs or of ordinary round logs, so 40 that they will present flattened bearing-surfaces to the feed-rolls F F, thereby preventing their rolling or tipping laterally thereon.

In front of the mill and of the cylinder O, I secure a log-feedway comprising track-stringers Q, secured upon foundations Q'. The stringers Q are cut away on their upper surfaces back from the cylinder O a sufficient 45 distance to receive the wheels of the front log-car, hereinafter referred to. Upon the stringers Q, I secure rails R, so as to form a track curving downward at the outer end *q* of the depression therein and curving upward at the opposite end *q'* of said depression, so as to operate as a stop for the car-wheels and prevent the car from contacting with the cylinder O. The log-cars operating on said tracks R are ordinary trucks having transverse bearing-beams T and provided with flanged wheels *t*, adapted to operate on the tracks R. In operation the quarter-logs or logs are loaded upon the trucks T T when standing on the level portion of the track R, but with the end of the quarter-log or logs next to the mill projecting some distance beyond the truck thereunder. The quarter-log or logs being then

50 moved toward the mill, the cylinder O skives off the under surface of the front end of the log, as illustrated by dotted lines in Fig. 2, and when the end of the log has passed upon the auxiliary feed-roll O' the front truck 70 passes down into the depression of the track and the log rests upon the auxiliary feed-roll O' and the rear truck, when the press-rolls are brought down upon it and it passes on upon the feed-rolls F F and is fed through the mill 75 in the usual manner.

Having thus shown and described my invention, so as to enable others to construct and use the same, what I claim as new, and desire to secure by Letters Patent of the United States, is—

1. In a gang-saw mill, the combination of a mill-frame, a saw-sash and mechanism for operating the same mounted in said frame, feed-rolls mounted in said frame, press-roll 85 yokes mounted on guides on said frame, press-rolls having V-shaped annular grooves therein mounted in said press-roll yokes, a leveling cutter-head operating on the under surface of the log and actuating mechanism in 90 the base of the mill-frame connected with and operating the press-roll yokes, substantially as set forth.

2. In a gang-saw mill, the combination of a mill-frame, a saw-sash, counterbalanced 95 mechanism operating said sash, feed-rolls mounted in said frame, press-roll yokes mounted on guides on said frame, two press-rolls, having V-shaped annular grooves, mounted in said press-roll yokes, a third and 100 central V-shaped press-roll mounted on the center of the press-roll yoke, and actuating mechanism mounted in the base of the mill-frame, connected with and operating the press-roll yokes, substantially as set forth. 105

3. In a gang-saw mill, the combination of a mill-frame, a saw-sash mounted therein, a main driving-shaft mounted in the base of the mill-frame, pitmen-cranks therein, pitmen connecting said cranks with the lower portion 110 of the saw-sash, a counterbalance-crank in said shaft, counterbalance-weights on arms pivoted to the base of the mill-frame, a pitman connecting the counterbalance-crank with the counterbalance-weights, feed-rolls mounted in the mill-frame, an auxiliary feed-roll 115 mounted in the front of the mill-frame on the same plane as the regular feed-rolls, press-roll yokes mounted on vertical guides on the mill-frame, press-rolls mounted therein, rock-shafts mounted in the mill-frame below the plane of the feed-rolls, links connecting the ends of the press-roll yokes with arms on said rock-shafts, steam or compressed-air cylinders mounted in the base of the mill-frame, 120 links connecting the piston-rods of said cylinders with arms on said rock-shafts, a transverse cylinder mounted in front of the idler-roll in the mill-frame, staggered cutters on 125 said cylinder the peripheries of which are on 130

a plane with the tops of the feed-rolls, mechanism for actuating said cylinder, a log-feed-way having a portion of the track thereof adjacent to the mill-frame depressed, and trucks 5 on said feedway-track, substantially as set forth.

4. In a gang-saw mill, comprising substantially a mill-frame, a saw-sash and mechanism for operating the same, feed-rolls, press-roll 10 mechanism, and a transverse cutter-cylinder in front of the mill-frame the top of which is on a plane with the tops of the feed-rolls of the mill, a log-feedway, a track thereon having a portion of it adjacent to the cutter-cyl-

inder depressed below the general plane of 15 the remainder of the track, trucks on said track adapted to convey logs into the mill, so that the cutter-cylinder will skive off and flatten the under surface thereof during their passage into and through the mill substantially as set forth. 20

In testimony whereof I affix my signature in presence of two witnesses.
